UNITED STATES PATENT OFFICE.

SAMUEL E. THOMAN, OF SHADYSIDE, OHIO.

FRUIT-PRESS.

1,137,808.

Specification of Letters Patent.

Patented May 4, 1915.

Application filed March 16, 1912. Serial No. 684,133.

To all whom it may concern:

Be it known that I, SAMUEL E. THOMAN, a citizen of the United States, residing at Shadyside, in the county of Belmont and State of Ohio, have invented a new and useful Fruit-Press, of which the following is a specification.

This invention relates to fruit presses, one of its objects being to provide a press of novel form having an apertured head and a compressing means coöperating therewith whereby the juice is expressed from the fruit in an efficient manner and the pulp is sheared off into minute particles, the apertures in the head being disposed in a novel manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a side elevation of a portion of a machine having the present improvements combined therewith. Fig. 2 is a central vertical section through the casing of the crushing mechanism, the worm being shown in elevation. Fig. 3 is a plan view of the bottom plate of the casing.

Referring to the figures by characters of reference 1 designates a supporting frame of any desired proportions and extending up to and over the top of this frame is an inclined frame 2 in which is arranged a conveyer 3 having a shaft 9.

A hopper 10 is located to receive the material discharged from the conveyer 3 and this hopper discharges into the upper end of a cylindrical casing 12. Said casing is preferably formed of sheet metal and in two semi-circular sections having flanges along their vertical edges as shown at 13, the flanges being bolted together or otherwise secured so as to hold the two sections securely together.

Annular ribs 14 are formed on the inner face of the casing 12 and the lower end of the casing is surrounded by a flange 15 upstanding from a bottom plate 16. This bottom plate has ears 17 outstanding therefrom and adapted to be fastened to the structure

1 in any preferred manner. This bottom plate 16 has a plurality of apertures 18 arranged therein in series, the apertures of each series being disposed in alinement and all of the series of apertures being extended tangentially from an imaginary circle at the center of the plate 16.

The plate 16 constitutes a crusher head adapted to coöperate with a worm 19 to crush the fruit supplied to the casing 12. This worm has a stud 20 extending downwardly and bearing within an opening 21 in the bottom plate 16.

A shaft 22 extends upwardly from the center of the worm and is journaled within a bracket 23 mounted on the top of the structure 1, said bracket likewise constituting a bearing for a shaft 24.

A bevel gear 25 is secured to the shaft 22 and meshes with a gear 26 secured to one end of the shaft 24. Another gear 27 meshes with gear 25 and is secured to a shaft 28 journaled on the structure 1.

Shaft 24 carries a gear 32 which is secured to said shaft and meshes with a gear 33 keyed or otherwise fastened to the shaft 9.

A sprocket 34 is secured to the shaft 24 and receives motion, through a chain 35, from another sprocket 36 secured to a drive shaft 37.

A hopper 51 is arranged under the crusher head 16 and is adapted to receive juice and pulp therefrom.

An inclined board 53 extends from a point below the hopper and is adapted to direct material into a conveyer 54.

It will be apparent that when the drive shaft 37 is actuated, motion is transmitted through sprocket 36, chain 35 and sprocket 34 to the shaft 24 and the worm 19 is thus rotated and the elevator 3 set in motion. The fruit to be pressed is placed on the elevator and carried upwardly. This fruit is then discharged into hopper 10 and gravitates into the casing 12 and onto the upper convolution of the worm 19. As the worm is rotated by the gears 26 and 25 the fruit is forced downwardly past the ribs 14, thus being initially cut or crushed by the shearing action of the worm upon the ribs. Finally the fruit is compressed on the crusher head or plate 16 and moved therearound by the lower or scraping end of the worm. The small portions of fruit are forced through the outlet openings 18, it having been found that by arranging the

openings shown and described a shearing action takes place between the end of the worm and the far edges of the openings 18. The crushed pulp is discharged through 5 openings 18 into the hopper 51.

Importance is attached to the fact that the crushing mechanism can be readily reached for the purpose of cleaning or repairing it. For example, by disconnecting the sections 10 of the casing 12 from each other they can be removed from around the worm 19 and said worm as well as the crusher head or plate 16 can thus be easily cleaned.

What is claimed is:—

15 The combination with a casing, of a head constituting the bottom thereof, said head having a plurality of series of slots, disposed tangentially to a circular area at the center of the head, said area being of small size 20 relative to the size of the head, each of said slots being provided with parallel sides and

being relatively narrow, all of the series of slots converging to form equal angles and extending from points close to the periphery of the head to points close to the center of 25 the head, and a worm mounted for rotation within the casing and having a single straight radial scraping edge at one end bearing against the head, said worm being pitched to compress material against the 30 head, said scraping edge of the worm and the far edges of all of the slots in the head co-operating to shear material inwardly toward the center of the head.

In testimony that I claim the foregoing 35 as my own, I have hereto affixed my signature in the presence of two witnesses.

SAMUEL E. THOMAN.
